CLAIM

The ornamental design for a “ceiling light,” as shown and described.

DESCRIPTION

FIG. 1 is a front, bottom perspective view of a ceiling light, showing my design;

FIG. 2 is a front, top, right perspective view thereof;

FIG. 3 is a cross-sectional view thereof;

FIG. 4 is a front elevational view thereof;

FIG. 5 is a right side elevational view thereof;

FIG. 6 is a bottom plan view thereof;

FIG. 7 is a top plan view thereof;

FIG. 8 is a rear elevational view thereof; and,

FIG. 9 is a left side elevational view thereof.

The broken lines in the drawings illustrate portions of the ceiling light which forms no part of the claimed design.
